UNITED STATES PATENT OFFICE.

BERTE FEDERLE, OF KEARNEY, NEBRASKA.

PIANO KEY.

Application filed April 30, 1924. Serial No. 710,042.

The invention relates to piano keys, and has for its object to provide a piano key to one side of the rocking point thereof with an adjustable weight frictionally held and 5 slidably mounted in an elongated recess in the key and forming means whereby the key may be properly balanced for light medium or heavy touch by the movement of the weight to various positions.

10 A further object is to provide a metallic lining for the recess having guide ribs disposed in grooves and opposite sides of the weight for holding the weight against lateral transverse movement. Also to form 15 the lining from a single piece of elongated metal having a rib, the ends of which strip are overlapped, thereby allowing the weight to be placed in the lining when out of the key recess, and securely held by the lining 20 after the lining has been placed in the key recess and secured therein.

With the above and other objects in view the invention resides in the combination and arrangement of parts as hereinafter set 25 forth, shown in the drawing, described and claimed, it being understood that changes in the precise embodiment of the invention may be made within the scope of what is 30 claimed without departing from the spirit of the invention.

In the drawing:—

Figure 1 is a perspective view of a conventional form of piano key, showing the device applied thereto.

35 Figure 2 is a vertical transverse sectional view through the piano key taken on line 2—2 of Figure 1.

Figure 3 is an enlarged longitudinal sectional view through the rear end of the 40 piano key.

Figure 4 is a perspective view of the lining.

Referring to the drawing, the numeral 1 designates a conventional form of piano 45 key, and 2 a bar on which the piano key rocks. The bar 2 is provided with an upwardly extending pin 3, which prevents displacement of the key in the usual manner, and at the same time allows a rocking there- 50 of on the bar 2. The rear end 4 of the key is provided with a conventional form of connection 5 whereby the key may be connected to cord striking mechanism. It has been found that keys are not properly adjusted or 55 balanced for light, medium or heavy playing, and that the end 4 thereof does not move

downwardly rapidly enough for medium or heavy playing. To obviate this difficulty the rear end 4 of the key is provided with an elongated chamber 6, preferably extending entirely through the key, and in which chamber a lining 7 is disposed. The lining 7 is provided with longitudinally disposed ribs 8 on its opposite sides, which ribs are disposed in oppositely disposed grooves 9 of a weight 10. Weight 10 is frictionally held 60 within the lining 7, and is adapted to be moved to various positions in relation to the rocking point of the key for accelerating the movement of the rear end of the key, for instance, for heavy playing the weight is moved to the end of the key in registration with the legend "Heavy." When a medium touch is desired, the weight is placed in registration with the legend "Medium," and 70 for a light touch in registration with the legend "Light." By frictionally holding the weight, it will be seen that securing means, for instance adjusting screws or set screws are obviated, and the device may be easily 75 adjusted by inserting a pin in the aperture 11 of the weight and moving the weight to the desired position.

The lining 7 is formed from a single piece of material having ribs 8 thereon, and is 80 bent to rectangularly shaped form as shown in Figure 4, with its angularly disposed ends 12 overlapped, therefore it will be seen that the weight can be placed in the lining 7 when the lining is out of the key, 85 and the lining with the weight therein may be easily and quickly placed in the chamber 6 of the key, and secured to the ends of said chamber by means of nails 13, consequently the weight is securely held against trans- 90 verse lateral displacement, and is friction- 95 ally held in a manner whereby it may be easily and quickly adjusted to various longitudinal positions according to the touch desired.

100 From the above it will be seen that a touch adjusting weight is provided for a piano key, which weight is frictionally held within a chamber of the key and may be easily and quickly adjusted to various posi- 105 tions. It will also be seen that the weight is entirely encased with the chamber of the key, and therefore will not necessitate the rearrangement in any way of adjacent mechanism.

110 The invention having been set forth what is claimed as new and useful is:—

1. The combination with a rockable piano key, of a touch adjusting weight carried thereby, said weight being frictionally held and slidably mounted in a chamber of the key and oppositely disposed ribs carried by the key in the chamber and engaging grooves in the weight.
2. The combination with a rockable piano key, of a touch adjusting weight carried thereby, said weight being frictionally held and slidably mounted in a lining in the chamber of the key, said lining being provided with oppositely disposed guide ribs disposed in opposite sides of grooves in the weight.
3. The combination with a rockable piano key, of a touch adjusting weight carried thereby, said weight being frictionally held in various adjusting positions within a chamber of the key, a lining for said chamber, said lining and weight having rib and groove connections.
4. The combination with a rockable piano key, of a touch adjusting weight carried thereby, said weight being frictionally held in various positions within a chamber in the key of greater length than the weight, a lining for said chamber, said lining and weight having rib and groove connections, said lining being provided with a split whereby said weight may be positioned within the lining before the lining is placed in the chamber of the key.

In testimony whereof I hereunto affix my signature:

BERTE FEDERLE
